UNITED STATES PATENT OFFICE.

HORATIO N. H. LUGRIN, OF WORCESTER, ASSIGNOR TO THE CUTTER TOWER COMPANY, OF BOSTON, MASSACHUSETTS.

LETTER-SHEET.

SPECIFICATION forming part of Letters Patent No. 429,575, dated June 3, 1890.

Application filed August 10, 1888. Serial No. 282,476. (No model.)

To all whom it may concern:

Be it known that I, HORATIO N. H. LUGRIN, a citizen of the United States, residing at Worcester, in the county of Worcester and State of Massachusetts, have invented certain new and useful Improvements in Letter-Sheets, of which the following, together with the accompanying drawings, is a specification sufficiently full, clear, and exact to enable persons skilled in the art to which this invention appertains to make and use the same.

The object of my present invention is to provide a letter-sheet adapted for personal correspondence, having facilities for safely and conveniently retaining, supporting, or carrying postage-stamps, currency, bills, and other small articles, such as are frequently sent by post.

To this end my invention consists in the letter-sheet having the embossed carrier-band formed therein, as hereinafter described.

In the drawings, Figure 1 is a view showing my improved letter-sheet with single carrier arranged in conjunction with the embossed vignette or trade-mark stamp. Fig. 2 illustrates the manner of using the carrier, and shows a sheet having a plurality thereof, with modifications in the arrangement of the carriers or bands, as for currency, &c., and variations in the style of embossing. Fig. 3 is a section of the letter-sheet transversely through the carrier-strip, and Fig. 4 is a section of the letter-sheet longitudinally through the carrier-strip.

Referring to parts, A denotes the letter-sheet, which is of any ordinary kind of writing-paper such as used for correspondence, and which may be of any usual size and shape, as commercial note, letter-cap, legal-cap, or other style.

B indicate slits or openings cut or formed through the paper sheet, preferably parallel to each other and at a short distance apart, so as to produce a narrow strip or band C, the edges c c of which are severed from the main body of the sheet, while the ends at d d are left attached thereto. The strip or band C is impressed or embossed with any suitable design or ornamentation in a manner to throw up the strip or band C from the letter-surface or to raise the edges thereof

above the edges of the sheet along the slits or openings B, so that a postage-stamp or other similar article can readily and conveniently be inserted beneath the band, as indicated at F, Fig. 2, the band serving as a carrier for retaining the stamp or other article, and preventing it from escaping or dropping from the sheet and becoming lost when the letter is opened.

The letter-sheet may have its carrier-band formed in connection with the embossed vignette or trade-stamp, as Fig. 1, or at other portion. The sheet can be provided with one, two, or more carrier-bands formed therein at such positions as desired, preferably at positions near the top or side, as shown, or where the embossed bands will not interfere with writing on the surface of the sheet.

For carrying bills or currency, the sheet can be made with a long upright band, as shown in Fig. 2, convenient for the bill to be tucked under and folded back into the center of the sheet. The slits B can be simply cut through the paper, or may be slots of greater or less width, as required.

By constructing the letter-sheet with bands or carriers embossed or thrown up as described a very useful, ornamental, and desirable article of writing-paper is produced.

It will be understood that I do not claim the forming of slits in a fabric to serve as a means for retaining articles mounted thereon, as I am aware that such practice is old.

What I claim as my invention, and desire to secure by Letters Patent, is—

A letter or writing-paper sheet adapted for postal correspondence, provided with a carrier band or bands, the edges of which are separated from the main sheet by slits or openings cut through the paper, while the ends are left attached, and with the portion which forms the band raised or thrown up from the letter-surface by embossing or ornamental impressions, substantially as described.

Witness my hand this 7th day of August, A. D. 1888.

HORATIO N. H. LUGRIN.
